Primary Examiner — Sheryl Lane(74) *Attorney, Agent, or Firm* — Brooks Kushman P.C.(57) **CLAIM**

The ornamental design for a leaf rake, as shown and described.

DESCRIPTION

FIG. 1 is an isometric view of the leaf rake;
 FIG. 2 is a front view of the leaf rake;
 FIG. 3 is a back view of the leaf rake;
 FIG. 4 is a top view of the leaf rake;
 FIG. 5 is a bottom view of the leaf rake;
 FIG. 6 is a left view of the leaf rake;
 FIG. 7 is a right view of the leaf rake; and,
 FIG. 8 is another isometric view of the leaf rake.
 The broken lines in the drawings depict environmental subject matter only and form no part of the claimed design.

1 Claim, 6 Drawing Sheets(56)
